UNITED STATES PATENT OFFICE.

WILLIAM H. MINER, OF CHICAGO, ILLINOIS.

MEANS OF SUPPORTING FACE-PLATES.

1,070,054.

Specification of Letters Patent. Patented Aug. 12, 1913.

Application filed March 10, 1913. Serial No. 753,253.

To all whom it may concern:

Be it known that I, WILLIAM H. MINER, a citizen of the United States, residing at Chicago, in the county of Cook and State 5 of Illinois, have invented a certain new and useful Improvement in Means of Supporting Face-Plates, of which the following is a full, clear, concise, and exact description, reference being had to the accompanying drawings, forming a part of this specification.

My invention relates to improvements in means of supporting face plates and parts connected therewith, including buffer stems 5 and diaphragm face plates in railroad passenger cars.

In passenger car construction the buffer stems in the buffing devices mounted on the car engage the buffing compression resisting members at one end, and at their other end engage with the face plate. The face plate bears the diaphragm face plate. In this construction on account of the weight of the parts named it has been found in the practical operation of railroad passenger cars that the buffer stems are subjected to considerable wear.

The object of my invention is to remedy this difficulty by providing a simple and 30 efficient means of supporting the face plate and the buffer stems connected thereto. I accomplish this object by securing brackets to the end of the car body, and preferably near the top thereof, to which rods are pivoted and downwardly extended and pivotally connected at their lower ends to the face plate, the rods serving the function of supporting the face plate, and thereby supporting the forward ends of the buffer stem.

40 In the accompanying drawings forming a part of this specification I have illustrated, and will hereinafter describe in this specification, a particular type of car to which the device embodied in my invention is applied, 45 though it will be understood that the same may be applied to various types of railroad cars, and by illustrating and describing my invention as applied to the particular type I do not intend to limit the broad nature 50 of my invention to the particular application shown.

In the drawings Figure 1 is an end view of a car body of a type having an end vestibule showing the supporting members constituting my invention in position. Fig. 2 55 is a side elevation of the end of said car

body. Fig. 3 is a top plan view thereof. Fig. 4 is an enlarged detail showing one of the brackets and the head of the rod connected thereto. Fig. 5 is a detail showing 60 an end view of the face plate with the supporting rod attached thereto. Fig. 6 is an enlarged detail illustrating the means employed of attaching one of the rods to the face plate.

In the drawings 7 represents a car body, 8 the vestibule thereof, 9 the roof, of which 10 represents the upper deck, 11 the lower deck, and 12 the hood.

13 represents the name plate extending 70 along one side of the car below the roof thereof, 14 a side door of the vestibule, 15, 15 hand-holes, 16 steps, 17, 17 vestibule windows, and 18 the end of the vestibule.

19 represents a diaphragm face plate forwardly extended from the end of the car about the end opening 20 of the vestibule. The lower ends 21, 21 of the diaphragm face plate 19 are secured to the face plate 22. Above the face plate 22 and resting thereon 80 is the foot plate 23. Suitably secured to the end plate 22 and at the rear face 24 thereof are the side stems 25, 25 of the buffer, and the center stem 26. The vestibule diaphragm cover 27 is secured between the diaphragm face plate and the body of the car. 85

47, 47 represent piston rods secured to the upper portion of the diaphragm face plate, the same extending into the vestibule and bearing the piston rod springs 48, 48. 90

All the foregoing parts are of usual construction, and are well understood.

Secured to the car body at the ends thereof, and preferably near the top of the end of the vestibule, are the brackets 28, 28, to 95 which are pivoted the downwardly extended rods 29, 29, the same being pivotally connected at their lower ends 30, 30 to the face plate 22. The brackets, rods and means employed of pivoting the same at either end 100 are the same on either side of the vestibule diaphragm cover, and I will therefore describe one of these members.

The bracket 28 comprises a base plate 31 adapted to be secured, preferably by means 105 of the bolts 32, 32, to the car body. Forwardly extended from the face of said plate is a pair of lugs 33, 33 spaced apart to receive the head 34 of the rod 29, the said lugs 33, 33 and the head 34 having transverse registering perforations to receive the pin 35, forming a clevis connection between 110

the bracket 31 and the rod 29. The pin 35 is provided with a head 36 at its one end, and a perforation 37 at its other end to receive the cotter pin 38 to secure the said pin 5 against accidental displacement. At its lower end the rod 29 is provided with a loop 39, having therein the perforation 40 to receive the trunnion 41 of the plate 42, which is secured by suitable means, preferably 10 rivets or bolts 43, 43, to one end of the face plate 22, thus forming a pivot connection between the face plate 22 and the rod 29.

The trunnion 41 of the plate 42 is provided with a perforation 44 to receive the 15 cotter pin 45 to secure the rod 29 against accidental displacement. The head 34 of the rod 29 is preferably detachable from the said rod, and adapted to be screwed thereon, as indicated at the numeral 46 in Fig. 4 20 of the drawings, so that the length of the rod 29 may be suitably adjusted.

It will be apparent that the rods 29, 29 through their connection by means of the brackets to the car body at one end and to 25 the face plate at the other end serve to hold the forward ends of the buffer stems against downward displacement, and thus prevent the wear of the said stems, such as occurs when the same are supported by means frictionally engaging the said stem, and that 30 the diaphragm face plate and other parts connected thereto above the face plate 22 are held in position by the novel means described.

35 I claim:—

1. In a railroad car, in combination, a car body, a face plate at the end thereof, and means of supporting the same comprising rods, said rods being each secured at 40 one end to the car body and at the other end to the face plate.

2. In a railroad car, in combination, a car body, a face plate, and means of supporting the face plate comprising rods, the said 45 rods being each pivotally secured to the car body and to the face plate.

3. In a railroad car, in combination, a car body and a face plate, and means of supporting said face plate comprising brackets 50 secured to the car body, and single rods

extending between said brackets and the face plate.

4. In a railroad car, in combination, a car body and a face plate, and means of supporting said face plate comprising brackets, 55 rods and pins, the said rods being secured at one end to the face plate, and being provided at the other end with a perforated head, the said brackets being each provided with lugs adapted to receive one of said heads between them, and one of said pins passing through said lugs and the head between the same.

5. In a railroad car, in combination, a car body, a face plate, rods and brackets, the 65 face plate being provided at either end with a trunnion, a rod engaging each of said trunnions at one end, the said rods being each connected at the other end to one of said brackets.

70 6. In a railroad car, in combination, a car body, a face plate, a pair of brackets, a pair of rods, and a pair of plates, one of said plates being secured at either end of the face plate, a rod secured to each of said 75 plates, each rod being connected at its upper end to one of said brackets.

7. In a railroad car, in combination, a face plate, buffer stems secured thereto, a car body, and means of supporting said 80 buffer stems and face plate comprising rods pivoted at one end to the car body and at the other end to the face plate.

8. In a railroad car, in combination, a car body, buffer stem, and means of supporting 85 the same comprising a face plate and rods, the said face plate being connected to the buffer stem, and the rods each pivotally engaging the car body at its one end and the face plate at its other end.

9. In a railroad car, in combination, a face plate, a diaphragm face plate, and buffer stems secured to the face plate, rods each pivotally connected to the car body at 90 its one end and to the face plate at its other end.

95 WILLIAM H. MINER.
